[57] CLAIM

The ornamental design for the electrical outlet block, as shown and described.

DESCRIPTION

FIG. 1 is a perspective view of an electrical outlet block according to the invention, illustrating the outlet covers moved to their closed position;

FIG. 2 is a left side view of the electrical outlet block of FIG. 1;

FIG. 3 is a top view of the electrical outlet block of FIG. 1;

FIG. 4 is a front of the electrical outlet block of FIG. 1;

FIG. 5 is a right side view of the electrical outlet block of FIG. 1;

FIG. 6 is a bottom view of the electrical outlet block of FIG. 1;

FIG. 7 is a rear of the electrical outlet block of FIG. 1; and,

FIG. 8 is a perspective view of the electrical outlet block of FIG. 1, illustrating the outlet covers moved to their open position.

The broken line showing is included for the purpose of illustrating environmental structure only and forms no part of the claimed design.
